UNITED STATES PATENT OFFICE.

EDWARD MCCLINTOCK, OF MERRIAM PARK, MINNESOTA.

LOCOMOTIVE-ENGINEER'S ALARM.

SPECIFICATION forming part of Letters Patent No. 738,468, dated September 8, 1903.

Application filed February 5, 1903. Serial No. 142,084. (No model.)

To all whom it may concern:

Be it known that I, EDWARD MCCLINTOCK, of Merriam Park, Ramsey county, Minnesota, have invented certain new and useful Improvements in Locomotive-Engineers' Alarms, of which the following is a specification.

My invention relates to alarm mechanisms; and the object of the invention is to provide automatically-operating means for preventing head or rear end collisions on railroads by warning the engineers of both trains when they have approached within a certain predetermined distance of each other.

A further object is to provide means of warning an engineer when his train approaches an open switch, a burned bridge or culvert, a flooded section of track, or a train on another railroad at a crossing-point.

A further object is to provide means in connection with the signal whereby when the alarm has been sounded the engineers can establish a telegraphic or telephonic communication between their engines.

A further object is to provide signaling means to facilitate the switching of long trains, and a still further object is to provide means whereby a station agent can communicate with the engineer of a train that has passed a station without orders or through the misunderstanding of orders.

Other objects of the invention will appear from the following detailed description.

The invention consists generally in providing circuit-closing auxiliary rods or rails between or near the main-track rails and dividing them into blocks or sections that are insulated from the ground, the main rails, and each other, the rails on one side of each block at the ends thereof lapping by or breaking joints with the corresponding rails on the other side, and trucks arranged to run upon the main rails and said auxiliary or intermediate rails and insulated from each other and in circuit respectively with alarm-bells in the locomotive-cabs.

Further, the invention consists in providing continuously-operating pole-changing devices and means for automatically locking them when the circuit is closed by the presence of two trains in the same block or a damaged or flooded section of track that would derail a train entering that block.

Further, the invention consists in providing means in connection with a switch and a bridge or culvert which will close the circuit should the switch be left open or the bridge or culvert burned or flooded and sound an alarm in the locomotive-cab when the train enters the block in which the switch, bridge, or culvert may be located.

Further, the invention consists in various constructions and combinations, all as herein-after described, and particularly pointed out in the claims.

In the accompanying drawings, forming part of this specification, Figure 1 is a plan view of the mechanism that is placed in the cab of the locomotive, showing two independent circuits A and B to the trucks or shoes on the track-rails. Fig. 2 is a section on the line *xx* of Fig. 1. Fig. 3 is a detailed plan view of one of the pole-changing devices. Fig. 4 is a section on the line *zz* of Fig. 3, and Fig. 5 is a section on the line *yy* of Fig. 1. Fig. 6 is a plan view of the forward trucks of the locomotive, showing the auxiliary contact-trucks in position on the rails. Fig. 7 is a longitudinal section through the truck-frame, showing the manner of supporting the auxiliary trucks on the locomotive-frame. Fig. 8 is a detail sectional view of the auxiliary trucks, showing the means for yieldingly holding them on the rails. Figs. 9 and 10 are details of the insulating-joint between the auxiliary or small rails of the track. Fig. 11 is a side elevation of a locomotive, showing my invention applied thereto. Fig. 12 is a detailed view of the interior of the locomotive-cab, showing the position of the alarm mechanism therein. Fig. 13 is a plan view of a switch with my invention applied thereto. Fig. 14 is a detail of the same. Fig. 15 is a detailed view showing a device to be operated by the foot of the engineer to cut out the alarm mechanism when the engine is used for switching. Fig. 16 is a plan view of the cut-out mechanism, and Fig. 17 is a detail of the same. Fig. 18 is a transverse view of a bridge, showing a connection between the rails that will close the circuit in case a bridge is burned. Fig. 19 illustrates the manner of insulating the connecting-bars from the rails on a bridge. Fig. 20 shows circuit-closing devices used in connection with a bridge and

operating to close the circuit and warn the engineer of an approaching train in case of a flood and high water at the bridge. Fig. 21 is a plan view of a ninety-degree railroad-crossing. Fig. 22 is a similar view of a highway-crossing.

In the drawings, 2 represents a suitable base adapted to be secured in the cab of a locomotive and whereon the alarm mechanism is arranged. I have shown two independent pole-changing circuits, which I will designate as A and B, one connected with the main and auxiliary rails on one side of the track and the other with the corresponding rails on the other side, and as each circuit is a duplicate of the other it will be sufficient in this case to describe one of them only, the functions and operations of the other being substantially the same. The necessity of employing two circuits will hereinafter appear.

3 and 4 are semicircular plates (see A circuit) secured to the base 2 and having their ends insulated from each other by being suitably spaced or separated by an insulating material, as desired. These plates form the contacting surfaces over which the wheels of the A-circuit pole-changer operate. 5 is an axle loosely and centrally mounted on the stud 6 and yieldingly held against vertical movement by a spring 13, provided on said stud between its head and the axle. 8 and 9 are wheels mounted on the ends of the axle 5, of insulating material, in bearings 10 and 11 and travel over the plates 3 and 4 and are yieldingly held thereon by the spring 7. An arm 12 is mounted on the stud 6 and connected with the ends of the axle 5 by coiled springs 7, which allow movement of said arm independently of the axle, and a link 14 pivotally connects the end of the arm 12 with a rod 15, that is arranged to reciprocate in guides 16 on said base 2. The rod 15 is connected by a pitman 17 with a crank-pin 18 on a gear 18', that is mounted in bearings in a bracket 19 on the said base, and the teeth of said gear mesh with a pinion 20 on a shaft 21, that is also mounted in said bracket and is provided with a driven pulley 22, which is connected by a belt 23 with a pulley 24 on a tumbling-rod 25, arranged on the locomotive-boiler and connected by a knuckle-joint with a rod 26, that is driven by a beveled-gear mechanism on a shaft 26', which in turn is operated by a belt from the forward trucks of the locomotive. The gear mechanism and the belt connection being of ordinary construction are not shown or described in detail herein. The speed at which the pulley 22 is driven can of course be readily regulated by the size of the pulley employed on the tumbling-rod and the gears connecting said rod with the truck. The rapidity of reciprocation of the rod 15 can also be governed by the gear connection between the pitman 17 and the pulley.

65 The contact-plates 3 and 4 and the wheels traveling thereover form the pole-changer of the A circuit, and on the other side of the

rod 15 I provide a duplicate pole-changer for the other or B circuit. These independent circuits are necessary to prevent the possibility of two trains meeting at the abutting ends of two blocks.

27 represents the main-track rails, and 28 and 29 small auxiliary rails that are arranged parallel with each other and with the main rails between the latter near the middle of the track or close to said main rails on the inside or on the outside, if preferred. These small rails are of any suitable conducting material and are insulated from the main rails, the ground, and each other. In some cases it may be preferable to arrange these auxiliary rails directly upon the flanges of the main rails, insulating them therefrom; but for convenience of illustration I have shown them arranged about midway between the said main rails. I provide insulation 30 between the joints of the rails 28 and 29, dividing them into sections or blocks that are preferably six miles long, the insulation on one side alternating half-way of each block with that on the other side, so that the ends of the blocks lap by or break joints with each other, as shown in Fig. 6, and the rails on one side of each block being in the A circuit and the corresponding rails on the other side in the B circuit it will be impossible for the trains to approach nearer than three miles of each other without one of the circuits being closed in both engines and the alarm sounded.

31 is a locomotive truck-frame wherein the trucks 32 are mounted, and upon said frame an auxiliary frame 33 is pivoted, wherein axles 34 and 35 are mounted. Trucks 36 and 37 in the A circuit are mounted on the axles 34 and insulated therefrom and from each other by bushings 38. Similar trucks, 39 and 40, for the B circuit are mounted on the shaft 35 and are insulated therefrom in the same manner as the trucks of the A circuit. The bearings 41 for the shafts 34 and 35 are slidably mounted on rods 42, that are pivotally connected with the downwardly-turned ends 43 of a plate 44, that is bolted to the truck-frame 31. Springs 45 are provided on the said rods 42 and yieldingly hold the said bearings 41 depressed and the trucks of both circuits in contact with the main and auxiliary rails of those circuits with a yielding pressure. (See Figs. 7 and 8.) Binding-posts 46 and 47 are provided for the trucks of both circuits, and wires 48^a and 49^a connect the posts of the A circuit respectively with a post 50^a and with a telegraph-key 51, mounted on a plate 52^a on the base 2. A section of wire 53^a connects the post 50^a with the wheel 9 of the A-circuit pole-changer and is suitably coiled to allow movement of the wheel back and forth over the contact-plates. A wire 54^a leads from the key 51 of said circuit to a post 55, that is connected by a wire, similar to the wire 53^a, with the other wheel 8, also of the A-circuit pole-changer. An electromagnet 56^a is mounted on the plate 52^a,

and wires 57^a and 58^a lead therefrom respectively through a battery to the contact-plates 3 and 4 of the A-circuit pole-changer.

59^a is the magnet-armature pivoted on the 5 plate 2 and held out of contact with the magnets by a spring 60 and pivotally connected with a pin 61, that reciprocates in guides 62 on said plate. This pin has a tapered end adapted to enter notches 63 10 in a rod 64^a, that reciprocates in guides 65 on said plate and is pivotally connected by a link 66 with the axle 5 of the A-circuit pole-changer between its pivot and the wheel 9. The oscillation of said axle will consequently 15 impart a reciprocating longitudinal movement to the rod 64.

If a similarly-equipped locomotive enters a block from either direction while another locomotive is in that block, the circuit A will 20 be closed through the wires 48^a and 53^a to the wheel 9, through the wire 58^a, from the magnets to the plate 4, from the plate 4 through the wires 53^a and 54^a to the key 51, and from the key 25 through the wire 49^a to the truck 37, thence along the rail and through the corresponding 30 circuit of the other locomotive to the outer rail, closing the circuits simultaneously in both locomotives. The closing of the circuit will energize the magnet and attract the armature 35 59^a, move the pin 61 into one of the notches 63 in the rod 64 and lock said rod against reciprocation, and the axle 5 against further movement over the contact-plates. If the locomotives approach each other on adjacent 40 blocks and come within the three-mile limit, assuming that to be the danger zone, the A circuit will be closed, provided the contact of the rails on that side is unbroken; otherwise the B circuit will be closed. To sound 45 an alarm when the circuit is closed in this manner, I prefer to provide an independent bell-circuit in connection with each of the circuits A and B.

67^a represents a bell of the A circuit, connected by a wire 68^a, that passes through a 50 battery and is attached to a spring-arm 69^a on the pin 61. 70^a is a wire connecting the other side of the bell with a clip 71 on the base 52^a and supporting an adjustable contact-screw 72, that is in the path of the arm 69^a. The attraction of the armature 59^a by its magnet will draw in the pin 61 and the arm 69^a, closing the alarm-bell circuit and sounding the alarm in both engines. As soon 55 as the bell begins to ring the engineers, being notified of the proximity of other engines, will by means of the telegraph-keys 51 in each cab communicate with each other through the bells and the Morse code or any other 60 system of signaling, if preferred. A telephone attachment may also be used in connection with or in place of the telegraphic key, if desired. To prevent movement of the pole-changers of the closed circuit and the 65 rods 64 during the operation of telegraphing from one engine to another while the engines are in motion, I prefer to provide a key 73,

secured on the base 52^a near the rod 64 and adapted to enter the notches 63 without in any way interfering with the movement of 70 the pin 61. Whenever, therefore, the engineers desire to communicate with each other, they will press the keys 73 and lock the pole-changers, which will be released by the pins 61 as soon as the circuits are broken by the 75 movement of the keys. While the engine is in motion both pole-changers will be oscillated continuously, changing the poles of their respective circuits from positive to negative, and vice versa, the use of pole-changers 80 being necessary through the presence of a battery in all locomotives, and as each locomotive is equipped with a similar apparatus having continuously-operating pole-changers 85 a circuit will always be established through one of the circuits A or B and through each locomotive as soon as they enter the same block regardless of which direction the trains are moving. The circuit B, through the trucks 39 and 40 and the rail 29 and the adjacent 90 main rail 27, will be closed in a similar manner to the circuit A, above described, and with locomotives equipped with both of these circuits and continuously-operating pole-changers it will be impossible for them to be 95 in the same block either going in the same or opposite directions or approach each other within a certain predetermined distance on different blocks without one of the circuits being closed through both locomotives and 100 both alarm-bells sounded.

The B circuit is constructed and operates in the same manner as the one described, and hence requires no detailed description. I have used the exponent *a* with the reference-figures for the more important parts of the A circuit, and to avoid confusion I employ exponent *b* with the corresponding reference-figures of the B circuit.

To prevent a train from running into an 110 open switch, I insulate a section 74' of the main track, as shown in Fig. 13, and provide a box 74 between the switch-stand 75 and the track and having a series of contact-plates 75^a and 76^a and 75^b and 76^b. Wires 77^a and 78^a connect the plates 75^a and 76^a with the track-rails of the A circuit, and similar wires 77^b and 78^b connect plates 75^b and 76^b with the track-wires of the B circuit, as indicated by the diagram Fig. 14. A plate 80 is slidably arranged within the box 74 and provided with a series of spring-fingers 81^a and 82^a and 81^b and 82^b, arranged in pairs on plates 81' in the A and B circuits, that are insulated 125 from each other. Movement of the sliding plate 80 causes contact between the spring-fingers and the plates 75^a and 76^a and 75^b and 76^b, so that if a train having its locomotive equipped with a signal mechanism approaches the switch from either direction one of the 130 circuits will be closed and the alarm-bell sounded as soon as it enters the block in which the switch is located. Any suitable means may be provided for operating the

plate 80 from the switch-stand mechanism; but I prefer to provide an arm 83 on the switch-rod 84. Movement of the arm 84 will impart a corresponding movement to the plate 80 and close or break the circuit through the spring-arms, according to the direction in which the rod is moved.

It is sometimes desirable to render the mechanism inoperative—as, for instance, when the engine is used in switching at a station or yard—and I therefore provide a plate 84, secured in the cab, and mount binding-posts 85^a and 86^a thereon and insulate them from each other and connect them with the wires 15 of the A circuit, and I also provide posts 85^b and 86^b, connected with the wires of the B circuit. Between these wires I provide a pivoted foot-operated lever 87, having contact-plates 88^a and 89^a and 88^b and 89^b arranged to engage contact-points 90^a and 91^a and 90^b and 91^b. When the engine is to be used for switching, the engineer will place his foot on the lever 87 and pressing down on the same against the tension of a spring 25 87' break both of the A and B circuits, cutting out the entire alarm apparatus until such time as the lever is allowed to return to its normal position.

In Fig. 18 I have shown a portion of a 30 wooden bridge, which I designate by reference-numeral 92. The main and auxiliary rails are laid upon the timbers of the bridge in the usual manner, and to warn the engineer of an approaching train in case the 35 bridge is burned I provide bars 93^a and 93^b, connecting the rails of the A and B circuits. The bars are preferably hooked over the flanges of the rails at one end and at the other are connected to the flanges of the other 40 rails by bolts 94, that are insulated from said flanges by bushings 95. (See Fig. 19.) Should the bridge be destroyed by fire, the bushings will be consumed and the bolts coming in contact with the rail-flanges will close the 45 circuits, and should a locomotive approach the bridge from either side an alarm will be sounded to notify the engineer that the bridge is in a dangerous condition. In Fig. 20 I have shown a bridge equipped with mechanism 50 for closing the circuits in case of a flood, where the bridge becomes dangerous to cross because of the high water. This circuit-closing means consists in arranging a timber 96 below the bridge-timbers and supporting it upon a series of hangers 97, arranged at the 55 ends and near the middle portion, preferably, of the timber 96. A series of arms 98^a and 98^b are mounted on the timber 96 below the main and auxiliary rails, there being one pair 60 of arms for each rail and the flanges of the rail-base resting on the bridge-timbers between the arms of their respective pairs. The arms are provided with teeth 99, and the arms of each pair are connected by wires 100^a and 100^b, and the adjacent arms of the pairs in the same circuit are connected by wires 65 101^a and 101^b. When the water rises suffi-

ciently high to float the timber 96, the arms will be raised and a circuit established from each auxiliary rail to the adjacent main rail. 70 I may use both of these devices on a bridge, so that an engineer will be notified when the bridge is in a dangerous condition either from fire or high water. In Fig. 21 I have shown a ninety-degree railroad-crossing and I have 75 connected the rails of the A circuit of one railroad with the corresponding rails of the same circuit on the other railroad by wires 102^a and 103^a, and in a similar manner have connected the B circuits of the two railroads by wires 102^b and 103^b. The rails to which the wires are connected are insulated from the intersecting portions of the track on the crossing. If two trains are approaching each other on the same track, an alarm will be 80 sounded in both engines as soon as they enter the block upon each side of the crossing. An alarm will also be sounded in each locomotive if a train is approaching the crossing on both of the railroads. 85

In Fig. 22 I have shown the rails of an ordinary street or highway crossing, where a section of the middle rails is insulated at each end and wires 104^a and 104^b connect the auxiliary rails and lead around the insulated 90 section. This insulated section of the middle track prevents short-circuiting of the alarm system in case a metallic connection should be made between the rails, as when a sleigh with metallic runners or a wagon is 100 passing over the crossing.

The operation, briefly, of my alarm system is as follows: The apparatus being installed in the cab of a locomotive and connected with some moving part, the pole-changing devices 105 will be oscillated, moving back and forth over their contact-plates and continuously changing the poles while the engine is in motion. If two locomotives are approaching each other either in the same or adjacent blocks or two 110 locomotives are similarly situated moving in the same direction, either the A or B circuit through both locomotives will be closed, the pole-changers for that circuit will be automatically locked, the alarm circuits 115 closed, and the bells sounded. The engineers can then by means of the keys and the bells communicate with each other, ascertain the distance between them, and compare their orders. If a train approaches a burning or 120 flooded bridge, the circuit will be closed in a similar manner and a wreck averted. A station agent can signal to an engineer of a train after it has passed a station, and by merely connecting the rails with a chain or iron bar 125 the brakeman at the rear end of a long train can communicate with the engineer and greatly facilitate the handling of long freight or other trains.

I have shown each pole-changer circuit 130 equipped with a battery for supplying the electrical energy necessary for the successful operation of the device; but it will be understood that a dynamo may be used instead

of the batteries, if preferred. The abutting ends of the auxiliary rails except at the ends of the blocks will be connected by copper or other wire to insure a good contact and transmission of the current from one rail to another in each block.

I have shown my invention used in connection with a steam railroad; but it is also applicable for electric roads, and where so used 10 I may prefer to increase the number of auxiliary rails to four and avoid using the main rails.

The mechanism I have shown and described 15 for carrying out my invention may be simplified, and I do not wish to be confined to the details of construction herein shown, the essential feature being the use of the pole-changing devices in each locomotive in circuit with rails that are divided into insulated 20 blocks with the rails on one sidelapping by those on the other side.

I claim as my invention—

1. The combination, with a locomotive and the track-rails, of the auxiliary rails divided 25 into insulating-blocks whose rails on one side lap by or break joints with the corresponding rails on the other side, trucks arranged to run upon said main and auxiliary rails and insulated from each other, a plurality of oscillating 30 pole-changing devices in the locomotive-cab and having independent electrical connections with the pairs of tracks forming independent circuits, operative connections provided between said pole-changing devices 35 and a moving part of the locomotive, a source of electrical energy for each circuit, and alarm-circuits in connection with each pole-changing circuit.

2. The combination, with the locomotive 40 and the track-rails, of the auxiliary rails divided into insulated blocks, trucks arranged to run upon said main and auxiliary rails and insulated from each other, a plurality of oscillating pole-changing devices having electrical 45 connections respectively with the pairs of trucks and forming two independent pole-changing circuits, means for driving said pole-changing devices continuously from a moving part of the locomotive, a source of 50 electrical energy, and alarm-circuits in connection with said pole-changing circuits.

3. The combination, with a locomotive and the track-rails, of the auxiliary rails divided 55 into blocks that are insulated from the main rails, the ground and each other, trucks arranged to run upon said main and auxiliary rails and insulated from each other, a plurality of oscillating pole-changing devices provided on the locomotive and each having 60 an independent circuit with one main rail and one auxiliary rail through said trucks, means for operating said pole-changing devices, and comprising a reciprocating rod operated between said pole-changing devices, 65 and links pivotally connecting said rod with said pole-changing devices, a source of electrical energy for said circuits and alarm-cir-

cuits provided in connection with said pole-changing devices.

4. The combination, with the track-rails, 70 of the auxiliary rails divided into insulated blocks whose rails on one side lap by or break joints with the corresponding rails on the other side, trucks arranged to travel upon said main and auxiliary rails and insulated 75 from each other, pole-changing devices located in the locomotive-cab and each having electrical connections respectively with one main and one auxiliary rail through the trucks thereon and forming independent circuits, means for operating said pole-changing devices continuously while the locomotive is in motion, a source of electrical energy for each circuit, alarm-circuits in connection with each pole-changing circuit, and means 80 for automatically locking the pole-changer when its circuit is closed and the alarm sounded for the purpose specified.

5. The combination, with the locomotive and the track-rails, of the auxiliary rails divided 90 into insulated blocks whose rails on one side lap by or break joints with the corresponding rails on the other side, two oscillating pole-changing devices arranged upon each locomotive and having independent electrical connections with one main rail and one auxiliary rail and forming two independent circuits, one of which will be closed through said rails when the locomotives are within a certain predetermined distance of each other 100 moving in the same or opposite directions or when one is stationary, means for operating said pole-changing devices continuously while the locomotives are in motion, a source of electrical energy in each locomotive, and 105 alarm-circuits arranged to be closed by the closing of a pole-changer circuit when two locomotives enter the same or adjacent blocks.

6. The combination, with the main and auxiliary rails, the latter divided into insulated 110 blocks whose rails on one side lap by or break joints with the corresponding rails on the other side, of pole-changing devices placed upon each locomotive and having independent electrical connections with one 115 main rail and one auxiliary rail, said circuits being normally open and one of them being closed when two locomotives enter the same block, means having yielding connections with said pole-changing devices for operating 120 them continuously while the locomotives are in motion, a source of electrical energy for each circuit, alarm-circuits arranged to be closed by the closing of a pole-changer circuit, telegraph-keys provided in said pole-changer circuits, means for automatically 125 locking a pole-changer when its circuit is closed, and manually-operated means for locking a pole-changer when its circuit is broken by the manipulation of a telegraph-key.

7. The combination, with the main and auxiliary rails, the latter divided into insulated blocks, of trucks arranged to travel

upon said auxiliary rails and insulated from each other, a pole-changing device provided upon each locomotive and having electrical connections with said trucks, means for operating said pole-changing device, a source of electrical energy for each pole-changing device, and alarm-circuits provided in connection with said pole-changing circuits and arranged to be closed and an alarm sounded in each locomotive when said pole-changing circuits are closed by the entrance of two locomotives into the same block, and magnets provided in said circuits, and reciprocating means actuated by the closing of the circuits through said magnets to lock said pole-changing devices.

8. The combination, with the main and auxiliary rails, the latter divided into insulated blocks whose rails on one side lap by or break joints with the corresponding rails on the other side, of trucks arranged to run upon said main and auxiliary rails and insulated from each other, pole-changing devices provided in each locomotive-cab and each having independent electrical connections with one main and one auxiliary rail through the trucks thereon, said pole-changing devices comprising plates insulated from each other and oscillating axles having wheels to rest upon said plates, a reciprocating rod having pivotal connections with said axles, means for operating said rod, a source of electrical energy for each pole-changer circuit, and alarm-circuits in connection with each pole-changer circuit.

9. The combination, with a locomotive and the track-rails, of the auxiliary rails divided into insulated blocks whose rails on one side lap by or break joints with the corresponding rails on the other side, trucks arranged to run upon said main and auxiliary rails and insulated from each other, pole-changing devices provided in the locomotive-cab and having independent electrical connections with the pairs of tracks through said trucks and forming independent circuits, means for operating said pole-changing devices, a source of electrical energy and an alarm-circuit for each pole-changer circuit, and a switch, and a mechanism arranged to close one of said circuits when the switch is open and a locomotive enters the block in which the switch is located.

10. The combination, with a locomotive and the track-rails, of the auxiliary rails divided into blocks that are insulated from the main rails, the ground and each other, trucks arranged to run upon said main and auxiliary rails and insulated from each other, pole-changing devices provided on the locomotive and each having an independent circuit with one main rail and one auxiliary rail through said trucks, and means for operating said pole-changing devices, a source of electrical energy for said circuits, and an alarm-circuit provided in connection with each pole-changer circuit, and means within control of the en-

gineer for cutting out both circuits, for the purpose specified.

11. The combination, with the main track 70 and the parallel auxiliary rails, the former having metallic connections at the joints and the latter being divided into blocks or sections that are insulated from each other, the insulating joints between the abutting auxiliary rails on one side lapping by or breaking joints with the corresponding joints of the rails on the other side, of trucks arranged to run upon said main and said auxiliary rails and insulated from each other, pole-changers having independent electrical connections with one main and one auxiliary rail through the trucks thereon, a source of electrical energy for each pole-changer circuit, and alarm-circuits connected with each pole-changer circuit to sound an alarm in each locomotive when they approach within a certain predetermined distance of each other, moving in the same or opposite directions, or when one locomotive is stationary.

12. The combination, with the main and auxiliary rails, the latter divided into insulated blocks whose rails on one side lap by or break joints with the corresponding rails on the other side, of trucks arranged to run upon said main and auxiliary rails and insulated from each other, pole-changing devices provided in each locomotive-cab and having independent electrical connections with one main and one auxiliary rail through the trucks thereon, said pole-changing devices comprising surfaces insulated from each other, and oscillating axles having contact-wheels to bear on said surfaces, and means for operating said axles, a source of electrical energy 105 for each pole-changer circuit, and alarm-circuits provided in connection with each pole-changer circuit.

13. In a device of the class described, the combination, with the pole-changer plates insulated from each other, of oscillating axles having contact-wheels to bear upon said plates, means for oscillating said axles, reciprocating rods yieldingly connected with said axles, pole-changer circuits, and means operated by the closing of said circuits to lock said rods and said axles.

14. In a device of the class described, the combination, with the oscillating pole-changers, and means for operating the same, of the notched reciprocating rods yieldingly connected with said pole-changers, pole-changer circuits, telegraph-keys provided in said circuits, reciprocating means arranged to engage the notches in said rods when said pole-changer circuits are closed, and manually-operated means for engaging said notches to lock said rods and pole-changers when said pole-changer circuits are intermittently opened and closed by the movement of said keys.

15. The combination, with a locomotive and the track-rails, of the auxiliary rails divided into insulated blocks whose rails on one side

lap by or break joints with the corresponding rails on the other side, trucks arranged to run upon said main and auxiliary rails and insulated from each other, pole-changing devices provided in each locomotive-cab and having independent electrical connections with the pairs of trucks forming independent circuits, said pole-changers comprising fixed contact-plates divided into insulated sections, and bearing contact-wheels arranged to reciprocate thereover, means for operating

7 said bearing-wheels, a source of electrical energy for each circuit, and alarm-circuits provided in connection with each pole-changing circuit.

15 In witness whereof I have hereunto set my hand this 17th day of January, 1903.

EDWARD MCCLINTOCK.

In presence of—

RICHARD PAUL,
C. G. HANSON.
